UNITED STATES PATENT OFFICE.

HENRY SCHOOLBERG, OF PITTSBURGH, PENNSYLVANIA.

VISIBLE CARD-INDEX RECORD.

Application filed November 30, 1926. Serial No. 151,620.

My invention relates to visible card index and record-recording means arranged in sheet form and adapted to be used in connection with a loose-leaf binder of the post type.

- 5 An object of the present invention is to provide an improved adjustable visible card index that may be employed in connection with a loose-leaf binder and arranged in book form.
- 10 A further object of my invention is to provide a construction embodying convenient and inexpensive means in sheet form for supporting index cards in a visible overlapping relation and a construction enabling any card 15 to be readily removed from or applied to the sheet without disturbing the other cards positioned on the sheet.

A still further object of the present invention is to provide convenient means for attaching the sheet-bearing cards to the posts of a loose-leaf binder.

In the accompanying drawings, which illustrate applications of my invention:

Fig. 1 is a face view of a sheet constructed 25 in accordance with my invention and showing a number of slightly overlapping index cards positioned thereon;

Fig. 2, a similar view showing another form 30 of card with a transparent thickened protective strip covering the index portion of the card;

Fig. 3, a perspective view showing a form 35 of card having a raised index strip portion thereon;

Fig. 4, a face view of a portion of a sheet 40 containing two columns of cards arranged thereon.

Referring to the drawings, and as preferred, 5 designates generally, a card-receiving sheet constructed in accordance with my invention. This sheet, as shown, includes a backing 6, or a backing 6^a made of any suitable thin flexible material, such, for example, as celluloid. 7 and 8 designate superimposed 45 side pieces of the same material as the backing, said pieces preferably secured to the backing 6 by having the longitudinally extending portions 7^a and 8^a of the said pieces pasted directly to the backing piece 6 along 50 the longitudinally extending opposite edges thereof. By securing only a portion of the superimposed pieces 7 and 8 to the backing, a free longitudinally extending portion of each piece 7 and 8 will be provided, these free 55 portions being designated by the characters 7^b and 8^b, respectively. By providing these free

portions 7^b and 8^b, card-receiving spaces between the backing 6 and the said portions 7^b and 8^b are formed, thereby enabling the cards or card-attaching means to be slidably positioned therein.

Each of the superimposed side pieces 7 and 8 is pasted to the backing 6 at the top of the sheet throughout its width as indicated at 7^c and 8^c and acts to prevent the cards from 65 sliding free of the sheet at the top thereof. The pieces 7 and 8 at their lower ends are likewise pasted for their entire width to the backing 6; these portions are indicated by 7^d and 8^d, and function to prevent the cards sliding 70 out at the bottom of the sheet.

The sheet construction just described constitutes a flexible frame for the index-bearing and record cards embodied in my invention. This frame, in the form of a sheet, is 75 provided at one side thereof with means for securing the sheets to the posts of a loose-leaf binder of the usual and well-known type, not shown. As illustrated, I employ notched tabs 9 for securing the sheets to the posts, these 80 tabs being preferably made of some suitable flexible material, such as cloth or leather.

In the drawings, I have shown several forms of visible index and data-recording cards 10. In the form of Fig. 2, the card 10^a 85 is formed with slits or slots 12, adapted to receive the reduced end portions 13 of a transparent protective strip 14. When a card of the form of Fig. 2 is employed, the index data is first placed on the card at the desired point 90 thereon, after which the protective strip 14 is applied to the card over the index portion.

In Fig. 3, I have shown the index portion 15 thereof slightly raised relatively to the body of the card 10^b. This raised or thickened portion is formed by superimposing one or more strips of a suitable material on the card, and, when a series of cards containing the said raised portions are assembled, the raised portions function to space the cards 95 and support them in the desired positions on the sheet. The transparent strip 14 constitutes the raised portion of the card of the form of Fig. 3.

In Fig. 4, 20 designates a superimposed strip or piece having two free portions 21 and 22, between which and the backing the extensions of the cards are designed to be placed; in this form the cards are also spaced 100 by the strips.

It will be understood that both faces or 105 pages of a sheet may be constructed as shown

and described with reference to one face or page, and the cards positioned on the second face in the same manner as above described.

What I claim is:

- 5 1. In a visible card index, a sheet having a flexible tab to engage a post projecting from an edge of the sheet, said sheet having superimposed side pieces arranged to provide card-receiving spaces between the said side pieces and the sheet, a series of cards entered in the said spaces, said cards each having a raised portion shorter than the distance between the side pieces whereby when the cards are mounted on the sheet, the raised portions 10 will contact one with another to position the cards on the sheet.
- 15 2. In a visible card index, a card-receiving sheet having attaching means for reception in a loose-leaf binder and including a backing, longitudinally extending strips carried by the backing and forming with the backing card-receiving spaces therebetween, and a series of cards having their ends entered in said spaces, said cards having superimposed 20 transversely extending strips of less length than the card whereby when the cards are mounted on the sheet, said transversely extending strips will contact with one another to position the cards on the sheet.
- 25 3. In a visible card index, a sheet having superimposed side pieces extending longitudinally of the sheet and having free portions to form guideways between the sheet and the side pieces for removably holding the 30 ends of index cards therein, and a series of cards each having a transparent superimposed strip of less length than the distance between the side pieces, whereby when the cards are mounted on the sheet the superimposed strips will contact one with another to position the cards on the sheet.
- 35 4. In a visible card index, a sheet having superimposed side pieces extending longitudinally of the sheet and having free portions to form guideways between the sheet and the side pieces for removably holding the 40 ends of index cards therein, a series of cards each having a superimposed transversely extend-

ing strip of less length than the distance between the side pieces whereby when the cards are mounted on the sheet the superimposed strips will contact one with another to position the cards on the sheet, said cards having slots, and strip-attaching means at the ends of the strips engaging said slots.

50 5. In a visible card index, a sheet having spaced guide-ways, cards having their ends removably disposed in said guideways, and said cards each having a transversely extending thickened portion of less length than the distance between the guideways whereby when the cards are mounted on the sheet, the thickened portions will contact one with another to position the cards on the sheet.

55 6. A card for use in a card index sheet, comprising a card member adapted at its ends to engage guideways of a sheet, and a thickened portion on the card of less length than the distance between said guideways, whereby the thickened portions of adjacent cards 60 will contact to position the cards on the sheet.

65 7. A card for use in a card index sheet, comprising a card member adapted at its ends to engage guideways of a sheet, and a transparent strip superposed on the card and being of less length than the distance between said guideways, whereby the strips of adjacent cards 70 will contact to position the cards on the sheet.

75 8. A card for use in a card index sheet, comprising a card member adapted at its ends to engage guideways of a sheet, and a strip superimposed on the card arranged to contact with the strip of an adjacent card to position the cards on the sheet.

80 9. A card for use in a card index sheet, comprising a card member adapted at its ends to engage guideways of a sheet, a strip superposed on the card having a portion of less length than the distance between the guideways, whereby the strips of adjacent cards 85 will contact to position the cards on the sheet, and means whereby said strip and card member are separably connected together.

In testimony whereof I affix my signature.

HENRY SCHOOLBERG.
